WATERPROOF CLOTHING

George S. Yeaton, Dorchester, and Louis Blauer, Arlington Heights, Mass., assignors to American Rubber Company, Cambridge, Mass., a Corporation of Massachusetts

Application July 14, 1932. Serial No. 622,466

1 Claim. (Cl. 2—87)

Our invention relates to waterproof clothing, and more particularly to overlapping flap constructions for preventing rain and snow from being driven through the overlapping portions of such clothing.

We are aware that various forms of flaps and securing devices have heretofore been employed to prevent water and/or snow from being driven past the flap portions of such clothing. However, such flaps, where an effort has been made to prevent such passage of rain and/or snow, have involved complicated nesting flaps which require considerable effort on the part of the wearer to adjust. During a rain storm it is particularly difficult to carefully adjust nesting flaps and securing means carried by such flaps when the hands of the wearer are wet and possibly cold. In many such cases time is an important factor in closing the flaps. Much time is lost in nesting flaps or in securing fastening means carried by such nested flaps.

We provide a flap construction for weatherproof clothing which is relatively simple and expeditious to fasten and unfasten. In our construction one flap edge of each overlapping pair of flaps is turned outwardly in a U-shape to form a channel along the edge of the inner flap. This channel faces outwardly to catch any rain and/or snow which might work its way between the flaps. Permanent securing and spacing means are provided for maintaining the channel shape. The securing means for each pair of flaps are mounted beyond the open edge of the channel in the body of the flap so that the outer edge of the channel bears against the inner edge of the overlapping flap with some pressure. The shape of the channel somewhat distorts the material of the outer flap so that an effective seal is provided at the channel. The permanent wide spread channel effectively catches and diverts all rain and/or snow which is driven past the fastener elements. Where a cape is provided in addition to material of the main body of the clothing, the cape may be provided with such a closure construction.

The accompanying drawing illustrates a present preferred embodiment of our invention, in which

Figure 1 is a front elevational view of an open raincoat and cape embodying our invention;

Fig. 2 is a front elevational view of the raincoat in the closed position; and

Fig. 3 is a cross sectional view illustrating the flap construction of the coat taken substantially along the section lines 3—3 of Fig. 2.

Referring to the drawing, a waterproof garment, illustrated in the form of a raincoat, is provided with the usual body 1 having overlapping flap portions 2 and 4, and a cape 5 which is provided with overlapping flap portions 6 and 7. As

illustrated, the flap portions 2 and 6 are intended to overlap the flap portions 4 and 7, respectively. The flap portions 2 and 6 are provided with fastener elements 8 which may be of any preferred form for engaging complementary fastening elements 9 on the flap portions 4 and 7. For quick operation the fastening elements 8 and 9 may be made in the form of conventional snap buttons in which the elements 9 are inserted within springs at the bases of the elements 8.

The edges of the flap portions 4 and 7 are bent outwardly to form open channels 10 and 11, respectively. To preserve the shapes of the channels 10 and 11 rivets 12 extend through the bent portions of the flaps, and spacing washers 14, preferably of rubber, are disposed on the rivets between the inner surfaces of the channels. With this construction the channels are maintained in an open condition at all times so as to preserve their effectiveness in catching and diverting water and/or snow. If desired, the upper rivet 15 of each of the channels may omit the washer. This is particularly advantageous in the channel 11 where the rivet 15 is directly under the chin of the wearer.

The fastening elements 8 and 9 are positioned beyond the open mouths of the channels 10 and 11 so that the outer flap portions 2 and 6 engage the outer surfaces of the channels and are deflected thereby. This provides a firm engagement between the outer surfaces of the channel and the overlapping flap portion so as to form a tight seal. The presence of the open channels 10 and 11 diverts the water and/or snow which passes the fastening elements 8 and 9 thereby preventing the access of such snow and water to the inner clothing of the wearer.

The flap portions 2, 4, 6 and 7 may be provided with reinforcing layers 16 and their ends may be provided with reinforcements 17, if desired.

While we have shown and described a present preferred embodiment of our invention, it is to be understood that it may be otherwise embodied within the spirit of the invention and the scope of the appended claim.

Having thus described our invention, what we claim and desire to protect by Letters Patent is:

A closure for weatherproof clothing comprising a pair of overlapping flaps, the inner flap having its edge bent outwardly to form a channel, rivets and spacing elements for maintaining the channel in an open condition, and cooperating fastening means carried by the flaps, said fastening means being disposed laterally of the mouth of the channel whereby the outer surface of the channel bears against the inner surface of the outer flap when the flaps are closed.

GEORGE S. YEATON.

LOUIS BLAUE.
